UNITED STATES PATENT OFFICE.

J. B. SARGENT, OF NEW BRITAIN, CONNECTICUT.

DESIGN FOR A COFFIN-HANDLE.

Specification forming part of Design No. 1,571, dated April 29, 1863.

To all whom it may concern:

Be it known that I, J. B. SARGENT, of New Britain, in the county of Hartford and State of Connecticut, have produced a new and ornamental Design for Coffin-Handles; and I do hereby declare that the following is a full, clear, and exact description of the same, reference being had to the accompanying drawing, making a part of this specification.

The drawing represents a plan or top view of my design.

My design consists in a plate or bracket showing a wreath of leaves and acorns which surround a convex or spherical center plate, and which is ornamented by two large acorns forming the sockets for the handle, which is also ornamented by leaves and acorns.

To enable others skilled in the art to fully understand my design, I will proceed to describe it with reference to the drawing.

The design of the bracket A, which is intended to retain the handle B, is composed of a wreath of leaves *a*, intermingled with acorns *b* at various points. Said wreath surrounds the center plate C, which is raised or convex, forming a portion of a sphere, and which, in order to increase the effect, may be highly polished. The handle B is retained by two acorns *c*, extending nearly across the entire width of the bracket A and considerably larger than the acorns *b*, which are intermingled with the leaves *a*. The body of the

acorns *c* is highly polished, the cup being left dull, so as to produce a good effect.

The handle B, the two ends of which catch into the sockets formed by the acorns *c*, is ornamented by leaves *d* on or near to each end, and by a cluster of leaves *e* in the center, which are also intermingled with acorns *f*, similar to the wreath *a*. The ends of the handle next to the acorns *c* are left plain, and they may be highly polished, so as to contrast in a pleasing and effective manner with those parts of said handle occupied by the leaves *d e*.

The bracket A and handle B may be cast of brass and plated or colored in any other desirable manner, according to the coffin to which the same are to be attached, and they are secured to the coffin by means of screws passing through holes *g* in the bracket.

Having thus fully described my design, what I claim as new, and desire to secure by Letters Patent, is—

The wreath *a*, with acorns *b*, as shown and described, also, in combination with the wreath *a*, the spherical center plate C, also the acorns *c*, in combination with the wreath *a* and handle B, also the leaves *d* and *e*, with acorns *f* on the handle B.

J. B. SARGENT.
